Soland Blackfri

Attorney

UNITED STATES PATENT OFFICE.

JULIA CHAPATTE, OF TUXEDO PARK, NEW YORK.

AUTOMATIC HAND KNITTING MACHINE.

Application filed April 15, 1922, Serial No. 553,052. Renewed December 6, 1923.

To all whom it may concern:

Be it known that I, JULIA CHAPATTE, a citizen of Switzerland, residing at Tuxedo Park, in the county of Orange and State of New York, have invented certain new and useful Improvements in Automatic Hand Knitting Machines, of which the following is a specification.

This invention relates to a hand knitting machine, having particular reference to a small hand operated device of this kind, the invention having for an object the provision of a simple and inexpensive device of this kind by use of which the operation of knitting may be greatly facilitated, the invention being intended more particularly for knitting narrow tubular elements which may be used as ornamental braids.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of my improved knitting machine.

Fig. 2 is a plan view thereof.

Fig. 3 is an axial sectional view.

Fig. 4 is a detail perspective view of the cam ring.

Fig. 5 is a detail side elevation of the needle.

As here embodied my improved knitting machine comprises a cylindrical body 10 the axial passage through which is indicated at 11. Formed in one end of this body are a series of recesses or sockets 12, which extend parallel to the axis of the body 10 and are spaced evenly therearound. The depth of these sockets is here shown as about one-half of the length of the body 10 and they have diminished extensions 12' at their inner ends.

These sockets have slidably engaged therein the needles 14 whose outer ends project beyond the end of the body 10 and whose inner ends engage in the diminished extensions 12', the needles being urged outwardly by expansion springs 15 coiled around their inner ends and bearing against collars 16 fixed to the needles, these collars also serving to guide the needles by engaging the walls of the sockets 12. Fixed to the collars are pins 17 which project outwardly through

slots 18 in the body 10 and have heads 19 fixed to their outer ends.

Rotatably mounted on the body 10 is a ring 20 held against axial movement by a series of studs 21 fixed thereto and engaging in a circumferential groove 22 in the body 10. Upon the lower side of this ring 20 are a pair of diametrically opposed cam projections 23 adapted to engage the heads 19 of the pins 17 to depress the needles 14. Fixed upon this ring 20, and projecting beyond the end of the body 10 are a pair of sleeves 25 through which the thread or yarn to be woven is led from suitable skeins or balls.

The needles 14 have hooks 26 on their outer ends, and have pivoted thereto a short distance from their outer ends the latches 27 whose function is to permit of the loops of yarn sliding freely over the hooks.

It is believed that the manner of use of my improved knitting machine will be readily understood from the above description. The yarn is first passed around the needles under the latches 27 when the needles are in their uppermost positions, from the sleeves

and then inserted through the aperture 11, where it may be engaged by a hook 30 on a weight 31 attached by a chain 32 to the body 10, the yarn being thus held tensioned. The ring 20 is then given a rotary movement on the body 10, causing a second layer of yarn to engage the needles under the hooks 26 but above the latches 27. Immediately after this second layer of yarn engages the needles the latter are depressed by the cams 23 engaging the pins 17, this movement causing the latches 27 to swing up to closed position by reason of their engagement with the ends of the body 10, thus permitting the first layer of yarn to slip over the needles.

As the ring 20 rotates further, the springs 15 throw the needles forward and the layer engaged in the hooks 26 is moved downward along the needle and under the latch 27 which swings to accommodate this movement. This second layer is again discharged over the needle points after a third layer is caught in the hooks, the operation being repeated indefinitely, the knitted web passing down through the opening and may be kept under tension by hooking the weight 31 thereon, this weight being adjusted along the web as required. By feeding a pair of different colored strands

to the device I may obtain a knitted web

comprising two different colors as will be apparent.

Having thus described my invention what I claim as new and desire to protect by Letters Patent of the United States is as follows:

1. A device of the class described comprising a cylindrical body, a series of needles spaced around the axis of said body and projecting from one end thereof and being located in sockets formed in said body, said needles being parallel to the axis of the said body and movable longitudinally of themselves thereon, hooks and latches on said 15 needle, said latches being adapted to be closed on said hooks on inward movement of said needles in said body, pins on said needles projecting radially outward through slots in said body said slots leading from the 20 said sockets, a ring rotatable on said body, a pair of cam projections on said ring adapted to engage said pins to depress said needles, springs coiled around the inner ends of said needles and urging the same outward.

2. A device of the class described comprising a cylindrical body, a series of needles spaced around the axis of said body and projecting from one end thereof and being located in sockets formed in said body, said needles being parallel to the axis of the said body and movable longitudinally of themselves thereon, hooks and latches on said 30 needle, said latches being adapted to be closed on said hooks on inward movement of said needles in said body, pins on said needles projecting radially outward through slots in said body, a ring rotatable on said body, a pair of cam projections on said ring adapted to engage said pins to depress said needles, springs coiled around the inner ends of said needles and urging the same outward.

of said needles in said body, pins on said needles projecting radially outward through slots in said body said slots leading from the said sockets, a ring rotatable on said body, a pair of cam projections on said ring adapted to engage said pins to depress said needles, springs coiled around the inner ends of said needles and urging the same outward, and means for winding strands of 40 yarn across the outer faces of said needles. 45

3. A device of the class described comprising a cylindrical body, a series of needles spaced around the axis of said body and projecting from one end thereof, said needles being parallel to the axis of the said body 50 and movable longitudinally of themselves thereon, hooks and latches on said needle, said latches being adapted to be closed on said hooks on inward movement of said needles in said body, pins on said needles projecting radially outward through slots in said body, a ring rotatable on said body, a pair of cam projections on said ring adapted to engage said pins to depress said needles, springs coiled around the inner ends of said 55 needles and urging the same outward, and means for winding strands of yarn across the outer faces of said needles, said means comprising a pair of sleeves on said ring through which the yarn is passed, said sleeves being circumferentially spaced with respect to said cams. 60

In testimony whereof I have affixed my signature.

JULIA CHAPATTE.
